INK FEED MEANS FOR PRINTING PRESSES

Otto G. Bushman, Salt Lake City, Utah

Application March 22, 1938, Serial No. 197,520

5 Claims. (Cl. 101—364)

This invention appertains to new and useful improvements in feed means for printing presses. At present there is a tendency of the ink to "back up" in relation to the usual fountain roller of the press with the result that the ink is not evenly distributed on the roller with the consequent lack of uniformity in printing.

The principal object of the present invention is to provide means whereby the ink is placed under such a pressure as to prevent any tendency of the same from backing up and not properly applying itself against the fountain roller.

Other important objects and advantages of the invention will become apparent to the reader 15 of the following specification.

In the drawings—

Figure 1 represents a fragmentary top plan view of the improved fountain.

Figure 2 is a sectional view taken substantially 20 on the line 2—2 of Figure 1.

Figure 3 is an enlarged fragmentary sectional view taken substantially on the line 3—3 of Figure 2.

Figure 4 is a fragmentary perspective view of 25 the weight strip.

Figure 5 is a fragmentary top plan view of the ratchet means.

Figure 6 is an enlarged detailed sectional view 30 substantially on the line 6—6 of Figure 1.

Figure 7 is a sectional view on the line 7—7 of Figure 2.

Referring to the drawings wherein like numerals designate like parts, it can be seen that numeral 5 represents the usual ink fountain in 35 which the ink roll 6 is rotatably mounted.

The fountain has the inclined back 7 on which sets the elongated bar 8 and from this elongated bar extends the thin resilient plate 9 which has its free edge in close proximity to the roll 6 so 40 as to evenly distribute ink thereon and the spaced disposition of the free edge portion of the plate 9 with respect to the roll 6 is regulated by a plurality of threaded members 10 having winged heads 11 and these are feedable through 45 bores in the vertical portion 12 of the fountain and against the swingable arms 13, which arms are mounted to swing on the hinge pin 14 and are located under the resilient plate extension 9. The bar 8 is held by screws 15. The foregoing 50 is a conventional ink equalizer for printing presses and is of the type set forth in Patent No. 1,802,026, issued April 21, 1931, to S. B. Lestner.

In carrying out the present invention, the purpose is to force the ink under a substantial pres-

sure so that the plate extension 9 will serve its purpose of uniformly distributing the ink on the roll 6. To this end, an L-shaped bracket 16 is provided having its lower portion secured by one of the screws 15 to the inclined back 7, while the upstanding portion of the bracket 16 has the U-shaped block 17 secured thereto. Slidably disposed through this block 17 is the ratchet bar 18 and mounted in the block is the pawl 19 for engagement with the ratchet bar 18.

The lower end of the ratchet bar 18 is secured to the transversely arcuate elongated blade 20 embraced by fins or webs 21 radiating from the bar 18 and secured to the blade 20.

The rod 18 is provided with a plurality of 15 longitudinally spaced openings 22 into any one of which the headed pin 23 can be disposed for regulating the tension of the coiled compressible spring 24 which is interposed on the ratchet bar 18 between the upper end portion of the bracket 16 and the pin 23. The spring 24 serves to urge the blade downwardly to maintain a constant pressure on the ink. Furthermore, to keep the blade 20 urged downwardly so that its lower edge is against the resilient plate extension 9, 25 a weight strip 25 is provided, the same extending longitudinally along the back of the blade 20 and having notches 26 for engaging over lugs 27 on the blade and also a reduced intermediate portion 28 to avoid the longitudinal fins or 30 webs 21.

The purpose of the pawl 19 and ratchet bar 18 is to prevent the blade from backing up, when the roller 6 turns the ink in the fountain. In certain types of presses the shape of the blade 20 35 will have to be somewhat different, and perhaps more than one ratchet and spring assembly will be required.

While the foregoing specification sets forth the invention in specific terms, it is to be understood that numerous changes in the shape, size and materials may be resorted to without departing from the spirit and scope of the invention as claimed hereinafter.

Having described the invention, what is claimed 45 as new is:

1. In a printing press ink fountain having a bottom sloping toward an ink distributing roller, a member for pressing the ink toward the roller, said member being of plate-like form and extending across the fountain with its lower edge resting on the sloping bottom of the fountain and bodily movable in the fountain toward and away from the roller, a bar connected to the rear portion of said member and extending parallel to the slop- 50 55

ing bottom of the fountain and a guide at the rear of the fountain and through which the bar passes.

2. In a printing press ink fountain having a bottom sloping toward an ink distributing roller, a member for pressing the ink toward the roller, said member being of plate-like form and extending across the fountain with its lower edge resting on the sloping bottom of the fountain and bodily movable in the fountain toward and away from the roller, a bar connected to the rear portion of said member and extending parallel to the sloping bottom of the fountain and a guide at the rear of the fountain and through which the bar passes, said bar having rack teeth thereon and a dog in the guide member engaging the teeth for preventing upward movement of the bar but permitting the bar and the plate-like member to move toward the roller.
3. In a printing press ink fountain having a bottom sloping toward an ink distributing roller, a member for pressing the ink toward the roller, said member being of plate-like form and extending across the fountain with its lower edge resting on the sloping bottom of the fountain and bodily movable in the fountain toward and away from the roller, a bar connected to the rear portion of said member and extending parallel to the sloping bottom of the fountain and a guide at the rear of the fountain and through which the bar passes, said bar having rack teeth thereon and a dog in the guide member engaging the teeth for preventing upward movement of the bar but permitting the bar and the plate-like member to move toward the roller, and a spring on the bar for moving the bar and the plate-like member toward the roller.

4. In a printing press ink fountain having a bottom sloping toward an ink distributing roller, a member for pressing the ink toward the roller, said member being of plate-like form and extending across the fountain with its lower edge resting on the sloping bottom of the fountain and bodily movable in the fountain toward and away from the roller, a bar connected to the rear portion of said member and extending parallel to the sloping bottom of the fountain and a guide at the rear of the fountain and through which the bar passes, said bar having rack teeth thereon and a dog in the guide member engaging the teeth for preventing upward movement of the bar but permitting the bar and the plate-like member to move toward the roller, and a spring on the bar for moving the bar and the plate-like member toward the roller, and a weight member associated with the plate-like member for holding a lower edge of said plate-like member on the sloping bottom of the fountain.

5. In combination with an ink fountain of a printing machine having a bottom sloping toward an ink distributing roller in the fountain, a blade member of arcuate shape in cross section and extending longitudinally across the fountain with its lower edge resting on the sloping bottom and its concave face directed toward the roller, a bar connected with the convex face of the blade and extending upwardly and outwardly, a guide member connected with the rear edge of the fountain and through which the bar passes and a spring on the bar between the guide member and a projection on the bar for forcing the blade member bodily toward the roller.

OTTO G. BUSHMAN.
